UNITED STATES PATENT OFFICE.

MISREE KHAN, OF CINCINNATI, OHIO.

COMBINED DOOR AND STEP STRUCTURE.

Application filed June 10, 1922. Serial No. 567,339.

To all whom it may concern:

Be it known that I, MISREE KHAN, a subject of Amanullah Khan, Amir, of Afghanistan, residing at Cincinnati, in the county of Hamilton and State of Ohio, have invented certain new and useful Improvements in Combined Door and Step Structures, of which the following is a specification.

My invention relates more particularly to doors and steps for conveyances and operating means for opening and closing them.

The objects of my invention are to provide simple, convenient and efficient means for mounting and operating the doors and steps in unison and in such a manner that the doors will be slidably mounted and concealed within the casing of the body of the conveyance whereby they are prevented from swinging outwardly to cause accidents, and whereby the steps are in position for use in entering and leaving the conveyance only when the doors are open and are concealed within the casing of the body when the doors are closed thereby protecting the steps from damage, while at the same time so concealing the steps within the body of the conveyance as to prevent an unauthorized user of the car, such as a bandit, from finding an easy method of access to the interior thereof.

Another object of the invention is to provide means whereby a plurality of doors and steps may be easily moved to opened or closed position either separately or simultaneously.

Another object of the invention is to permit ingress and egress to and from the conveyance when it is located in a narrow or confined space and also when it is stopped in front of a street lamp or other similar object which would prevent the swinging door from being opened sufficiently to permit entering or leaving the conveyance.

My invention consists in providing doors slidably mounted in the casing of the body of the conveyance and steps slidably mounted in the lower part thereof and mechanism for operating said doors and steps in unison.

My invention also consists in the construction, combination and arrangement of parts as herein set forth and claimed.

In the drawings:

Fig. 1 is a side perspective view of a car embodying my invention;

Fig. 2 is a plan view on a reduced scale showing the right steps in open position;

Fig. 3 is a side elevation of the conveyance showing the right doors in partly open position;

Fig. 4 is a horizontal section taken on a plane corresponding to the line 4—4 of Fig. 3 and showing the steps, doors and operating mechanism therefor in plan elevation;

Fig. 5 is a similar view showing the doors and steps in closed position and the position of the operating mechanism therefor when in that position;

Fig. 6 is a vertical section taken on the line 6—6 of Fig. 5;

Fig. 7 is a perspective view of the door and step operating mechanism for one side of the conveyance;

Fig. 8 is a perspective view of one of the doors; and

Fig. 9 is a perspective view of the outside opening and closing handle.

The conveyance which I have used to illustrate the embodiment of my invention is an automobile 1 of usual construction except the body 2 which is slightly changed in form and dimensions especially in the front part thereof. I provide vertical channels 3 and 4 in the front side walls forward of doors 5 and 6 to receive said doors when in open position and vertical channels 7 and 8 in the rear side walls to the rear of doors 9 and 10 adapted to receive said latter doors when in open position. I also provide horizontal spaces 11 and 12, below the inner side walls and below the floor 14 leading to said channels, respectively. The doors are provided with wheels 15 mounted upon suitable run-ways 16 in the bottoms of said channels, respectively.

Immediately beneath the floor 17 of the conveyance I provide horizontal space-ways 18, 19, 20 and 21 to receive steps 23, 22, 24 and 25, respectively, and to permit said steps to be entirely concealed therein, as shown in Fig. 5, or to be slid outwardly for use, as shown in Fig. 4. The floor 17 is provided with two curved slots 26 and 27 and the door and step operating mechanism comprises, on each side, hand operating lever 28 extending upwardly through one of said slots and is pivotally mounted on pivot bar 29 connected to fixed pivot 30. Each front connecting bar 31 is pivotally connected to said handle and to intermediate connecting bar 32. Each front connecting arm 33 is pivotally attached at one end at the joint 34

100 105 110

and is pivotally connected at the other end to lug 35 on front door 5 or 6. It is also pivotally attached between its ends to stud 36 on front step 22 or 25. Each connecting arm 37 is pivotally connected to intermediate connecting bar 32 at joint 38 and has one end pivoted to lug 39 on doors 9 and 10 respectively, and the other end to stud 40 on rear steps 23 and 24, respectively. When thus connected the handle 28 when moved in the curved slot 26 from the position shown in Fig. 4 to the position shown in Fig. 5 will draw said doors to closed position and said steps to concealed position and reverse movement of said handle will again cause said doors and steps to assume the position shown in Fig. 4.

For the purpose of opening and closing the doors and steps, respectively, from the outside, I provide an opening 41 on each side having a hinged door 42 mounted thereover. A curved handle bar 43 is mounted in said hole and is pivotally attached at joint 34. It is preferably provided with a suitable pivotally mounted handle 44 which is adapted to project to the outer surface of the body of the car when in closed position, as shown in Fig. 5 and when the doors are in open position it will extend outwardly and downwardly, as shown in Fig. 4.

It will be seen that the driver can conveniently grasp either hand operating lever 28 and push it backwardly to the rear end of curved slot 26 or 27 for opening the door and steps and also push it forward to the front end of the slot to close the same. If he is on the outside of the car and wishes to open the doors and steps he simply pulls on the handle 44 whereupon the door and steps upon one side of the car will be opened and if he wishes to close the doors and steps he simply pushes handle 44 inwardly until the doors and steps will be closed.

It will be observed that my construction and arrangement eliminates projecting side handles which serve to catch and tear the clothing and which also mar the beauty of the car. The hinged door may be provided with a suitable lock (not shown) to prevent unauthorized opening of the doors.

While I have shown and described a particular construction it will be understood that my invention is capable of modification in the construction and arrangement of parts without departing from its scope or spirit as defined in the claims.

What I claim as new and desire to secure by Letters Patent is:

1. In a conveyance, front and rear doors mounted to simultaneously slide in opposite directions, front and rear steps adapted to be concealed within the body line of said conveyance and to be slid to open position for use, a lug on each door, a stud on each step, a pivotally mounted bar, a handle

thereon, a front connecting bar pivotally attached to said handle, an intermediate connecting bar pivotally attached to said front connecting bar, a rear connecting arm pivotally attached to the lug on said rear door and to the stud on said rear step and pivotally connected between its ends to said intermediate connecting bar, a front connecting arm pivotally connected to the lug on said front door and to the joint pivotally connecting said front connecting bar and said intermediate connecting bar and also pivotally connected to the stud on said front step, substantially as set forth and for the purposes specified.

2. In a conveyance, front and rear doors mounted to simultaneously slide in opposite directions, front and rear steps adapted to be concealed within the body line of said conveyance and to be slid to open position for use, a lug on each door, a stud on each step, a pivotally mounted bar, a handle thereon, a front connecting bar pivotally attached to said handle, an intermediate connecting bar pivotally attached to said front connecting bar, a rear connecting arm pivotally attached to the lug on said rear door and to the stud on said rear step and pivotally connected between its ends to said intermediate connecting bar, a front connecting arm pivotally connected to the lug on said front door and to the joint pivotally connecting said front connecting bar and said intermediate connecting bar and also pivotally connected to the stud on said front step and a curved guide-way through which said handle projects and in which it is moved when operating said mechanism to open and close said doors and steps, respectively.

3. In a conveyance, front and rear doors mounted to simultaneously slide in opposite directions, front and rear steps adapted to be concealed within the body line of said conveyance and to be slid to open position for use, a rear arm pivotally connecting the rear door and rear step, a front arm pivotally connecting the front door and front step, a pivotally mounted bar, a handle thereon, an arc-shaped guideway for said handle, a front connecting bar pivotally attached to said handle, an intermediate connecting bar pivotally attached to said front connecting bar and to said front connecting arm and also pivotally attached to said rear connecting arm, substantially as set forth and for the purposes specified.

4. In a conveyance, front and rear doors mounted to simultaneously slide in opposite directions, front and rear steps adapted to be concealed within the body line of said conveyance and to be slid to open position for use, a rear arm pivotally connecting the rear door and rear step, a front arm pivotally connecting the front door and front step, a pivotally mounted bar, a handle thereon, an

arc-shaped guideway for said handle, a front connecting bar pivotally attached to said handle, an intermediate connecting bar pivotally attached to said front connecting bar and to said front connecting arm and also pivotally attached to said rear connecting arm and a pivotally mounted handle bar connected to the joint between said front and intermediate locking bars and adapted to be drawn outwardly or pushed inwardly to operate said mechanism for opening and closing the doors and steps, respectively, substantially as set forth.

5. In a conveyance having operating mechanism of the class described, a pivotally mounted curved arm having a jointed handle adapted to be pushed inwardly or pulled outwardly to operate said mechanism and when in outward position to drop down out of the 10 way against the body of the car.

6. In a conveyance having operating mechanism of the class described, a pivotally mounted curved arm having a jointed handle adapted to be pushed inwardly or pulled outwardly to operate said mechanism and when in outward position to drop down out of the way against the body of the car and a door for closing and concealing said handle when the doors are in closed position.

30 7. In a conveyance, front and rear doors mounted to simultaneously slide in opposite directions, front and rear steps adapted to

be concealed within the body line of said conveyance and to be slid to open position for use, a rear arm pivotally connecting the rear door and rear step, a front arm pivotally connecting the front door and front step, a pivotally mounted bar, a handle thereon, a front connecting bar pivotally attached to said handle, an intermediate connecting bar 40 pivotally attached to said front connecting bar and to said front connecting arm and also pivotally attached to said rear connecting arm and means for guiding said handle when moving it to operate said mechanism. 45

8. In a conveyance, front and rear doors mounted to simultaneously slide in opposite directions, wheels on which said doors are mounted, front and rear steps adapted to be concealed within the body line of said conveyance and to be slid to open position for use, a rear arm pivotally connecting the rear door and rear step, a front arm pivotally connecting the front door and front step, a pivotally mounted bar, a handle thereon, a front connecting bar pivotally attached to said handle, an intermediate connecting bar 50 pivotally attached to said connecting bar and to said front connecting bar and also pivotally attached to said rear connecting 55 arm, all combined and adapted to operate, substantially as set forth and for the purposes specified.

MISREE KHAN.
